UNITED STATES PATENT OFFICE.

HOSFORD D. KELLOGG, OF PHILADELPHIA, PENNSYLVANIA.

DESIGN FOR A RADIATOR.

SPECIFICATION forming part of Design No. 33,390, dated October 16, 1900.

Application filed September 25, 1900. Serial No. 31,103. Term of patent 7 years.

To all whom it may concern:

Be it known that I, HOSFORD D. KELLOGG, a citizen of the United States, residing in the city and county of Philadelphia, State of Pennsylvania, have invented and produced a new and original Design for Radiators, of which the following is a specification, reference being had to the accompanying drawings, forming part thereof.

10 The leading feature of my design for a radiator is a body consisting of a tubular border and diagonally-arranged tubular members within said border.

Figure 1 represents a side elevation of a radiator embodying my design. Fig. 2 represents a longitudinal section thereof on line *xx*, Fig. 1.

In the drawings, A designates the body of a radiator, the same consisting of the tubular border A', the intermediate tubular piece B, 20 and the web C, the latter being composed of tubular members which extend in diagonal directions within said border.

Having thus described my invention, what I claim as new, and desire to secure by Letters 25 Patent, is—

The design for a radiator substantially as shown and described.

HOSFORD D. KELLOGG.
